(21) Appl. No.: **29/242,661**

CLAIM

(22) Filed: **Nov. 14, 2005**

The ornamental design for a mobile flat-panel monitor and computer cart, as shown and described.

(51) **LOC (8) Cl.** **14-02**

DESCRIPTION

(52) **U.S. Cl.** **D14/302**

FIG. 1 is a perspective view of the mobile flat-panel monitor and computer cart of the invention;

(58) **Field of Classification Search** D14/302-307,

FIG. 2 is a right side elevational view of the mobile flat-panel monitor and computer cart of FIG. 1;

D14/371-375, 391-398, 125-129; 345/104,
345/156, 168, 173, 901-905; 348/180, 184,
348/325, 739; 341/12; 248/917-924; 349/1,
349/2, 11, 62; 361/680-686; D24/185, 186;
D6/425, 426; D34/14; 108/25; 359/635

FIG. 3 is a left side elevational view of the mobile flat-panel monitor and computer cart of FIG. 1;

See application file for complete search history.

FIG. 4 is a front elevational view of the mobile flat-panel monitor and computer cart of FIG. 1;

FIG. 5 is a rear elevational view of the mobile flat-panel monitor and computer cart of FIG. 1;

FIG. 6 is a top view of the mobile flat-panel monitor and computer cart of FIG. 1; and,

FIG. 7 is a bottom view of the mobile flat-panel monitor and computer cart of FIG. 1.
